AGITATOR FOR WASHING MACHINES

Peter Eduard Geldhof, Syracuse, N. Y., assignor
to Easy Washing Machine Corporation, Syra-
cuse, N. Y., a corporation of Delaware

Application September 6, 1935, Serial No. 39,464

1 Claim. (Cl. 68—134)

My invention relates to washing machines and, more particularly, to a novel agitator or dolly therefor.

An object of my invention is to provide an agitator for a washing machine adapted to be mounted for oscillation in a washing tub or vat containing washing fluid and clothes, said agitator being so constructed and arranged as to effect a thorough washing of the clothes.

10 A further object of my invention is to provide an agitator adapted to be mounted for oscillation in a washing vat which is adapted to circulate the clothes and washing fluid in one circulatory direction around the vat, whereby the clothes are constantly changing their relative positions in the vat so as to continually present new clothes surfaces to the washing action of the agitator.

20 My invention further contemplates the provision of a novel agitator for a washing machine in which the blades are mounted on a central portion at an angle to the vertical, whereby the thrusts produced by the agitator in the opposite directions of rotation thereof are slightly unequal so that while the movement of the clothes and washing fluid is primarily oscillatory in character, the clothes and washing fluid tend, at the same time, to circulate in one direction around the vat accompanied by an upward and downward movement of the clothes.

25 More specifically, my invention contemplates the provision of an agitator for a washing machine in which the central portion thereof is a pyramid having a blade secured to each face thereof, said blades extending at an angle to the vertical whereby, upon oscillation of the agitator, the clothes and washing fluid are thoroughly agitated and cleansing of the clothes is effected in a minimum of time.

30 Other objects and advantages of my invention will be more apparent from the following description when taken in connection with the accompanying drawings, in which:

Figure 1 is a view of the agitator, in vertical section, showing the agitator mounted in a washing vat.

Figure 2 is a view taken on line 2—2 of Figure 1.

Figure 3 is a perspective view of the agitator showing the shape and manner of mounting the blades on the central portion.

Figure 4 is a view taken in the line 4—4 of Figure 3.

Figure 5 is a view taken on the line 5—5 of Figure 3.

The agitator of my invention is adapted to be mounted in a vat or tub 11 in which the clothes and washing fluid are placed. The washing vat may be of any desired shape, either square or, as shown in the drawings, circular in cross section. The agitator, generally indicated by the numeral 12, is preferably mounted centrally of the vat 11 and is driven by a shaft 13 extending upwardly through the bottom of the vat. The shaft 13 may be driven in an oscillatory manner 10 by any suitable mechanism, not necessary to be shown or described herein, since such driving mechanism is well known in the art to which this invention applies. Preferably, the shaft is driven in an oscillatory manner through an arc of 15 180°, more or less, and at a speed of about fifty or sixty oscillations per minute.

A sleeve 14 surrounds the shaft 13 and provides a bearing point for the shaft at 16. The sleeve 14 extends downwardly concentric with 20 the shaft, has a flange 18 adapted to engage the bottom of the vat and has a portion 17 which extends through the bottom of the vat. The projecting portion 17 of the sleeve is provided with threads for securing the sleeve to a member 19. 25 A plate 20, which is part of an apron which partially encloses the machinery for oscillating the shaft 13, is interposed between the member 19 and the bottom of the vat. Suitable packing 21 is provided to prevent leakage of cleansing fluid 30 from the vat around the sleeve when the sleeve is screwed tightly into the member 19.

The central portion of the agitator is hollow, as indicated in the drawings, and at its lower portion is provided with suitable bosses 22 extending inwardly from the inner side walls of the central portion of the agitator. The bosses 22, preferably three in number, are adapted to receive a bearing 23. The bearing is press fitted 35 into the bosses for oscillation with the agitator and has a running fit, as indicated at 26, on an enlarged portion 27 of the sleeve 14.

The top of the agitator shaft 13 is splined, as indicated at 28, which splines are adapted to intermesh with splines 29 formed in a collar 31. The collar 31 is press fitted into a bore formed in the top of the central portion of the agitator. A hollow cap 32 of any suitable shape is secured to the top of the agitator by means of a screw 33. A flat plate 36 forms the bottom of the cap and rests upon fins 37 which are integral with the central portion 38 of the agitator. The plate 36 is formed with flanges 39 and 40, the inner flange 40 of which closely surrounds the central 45 50 55

portion of the agitator while the outer flange is secured to the top portion of the cap 32.

The central portion 38 of the agitator has a downwardly and outwardly extending surface such as that presented by a cone or, as indicated in the drawings, the central portion is preferably a pyramid. While the pyramid may have any number of sides, it preferably has three faces 41 so that the angles formed at the corners 42 of the pyramid are 60° and, therefore, form relatively sharp angled projections which, when the agitator is oscillated, produce a scrubbing and rubbing effect on the clothes.

At the bottom of the agitator, the faces 41 are flared outwardly so that the bottom of the agitator is substantially circular. Each of the faces of the pyramid is provided with a blade 44. The blades 44 are preferably straight throughout substantially their entire length and each of them extends from one corner 42 of the pyramid diagonally across one face to the other corner so that each of the blades extends at an angle to the vertical. Toward the bottom of the central portion of the agitator where the pyramid is flared outwardly to form the circular base, as at 46, the blades are slightly curved in the direction of inclination of the blades to the vertical and merge into the base at 48. While the blades may extend the entire height of the pyramid, preferably, they extend through only about three-quarters of the height thereof, as shown in the drawings. Preferably, also, the blades are comparatively narrow near the top and gradually widen as they extend downwardly across the faces of the pyramid toward the bottom, the point of greatest width being at the point 49 slightly below the point at which the blades begin to curve into the base. From this point, the blades gradually become narrower and merge into the base.

When the agitator is oscillated by reason of the fact that the blades extend in the same direction at an angle to the vertical and are slightly curved in the same direction near the bottom of the agitator, they tend to exert a greater thrust

on the clothes and washing fluid when the agitator is rotated in the clockwise direction than when it is rotated in a counterclockwise direction.

While the horizontal component of the thrusts caused by opposite faces of the blades are nearly equal, there is sufficient difference between them to cause the clothes to move around the vat slowly in a clockwise direction. Thus, the clothes are caused, at times, to change their relative position in the vat so that new clothes surfaces are constantly being presented to the action of the agitator. The vertical components of the thrust exerted by the agitator tend to cause the clothes and washing fluid to be raised upwardly during the clockwise rotation of the agitator and to be thrust downwardly during the counterclockwise rotation thereof. This upward and downward movement of the clothes insures a thorough agitation of the clothes. During the oscillation of the agitator, the edges 42 of the pyramid, as well as the blades themselves, exert a substantial scrubbing action on the clothes without causing deterioration thereof.

It will be apparent from the foregoing description that the agitator of my invention is of new and novel design and that various modifications and changes may be made in the form and relation of parts thereof without departing from the spirit of the appended claim.

I claim:

An agitator for a washing machine adapted to be mounted in a vat containing clothes and washing fluid comprising a central pyramid having an outwardly flared portion toward the bottom thereof, each face of said pyramid having a substantially straight blade extending from one corner of said pyramid downwardly along the face at an angle to the vertical substantially to the adjacent corner of the pyramid, each of said blades being curved near the lower end and merging with the outwardly flared portion at the bottom.

PETER EDUARD GELDHOF.
